J. Q. SHERMAN

ADJUSTABLE FEED MANIFOLDING DEVICE

Filed March 14, 1921

UNITED STATES PATENT OFFICE.

JOHN Q. SHERMAN, OF DAYTON, OHIO.

ADJUSTABLE FEED MANIFOLDING DEVICE.

Application filed March 14, 1921. Serial No. 452,185.

To all whom it may concern:

Be it known that I, JOHN Q. SHERMAN, a citizen of the United States, and a resident of the city of Dayton, in the county of Montgomery and State of Ohio, have invented certain new and useful Improvements in Adjustable Feed Manifolding Devices, of which the following is a full, clear, and exact description, reference being had to the accompanying drawings, forming part of this specification.

My invention relates to manifolding devices having an adjustable feed whereby the paper may be fed a desired distance over the machine writing table, and also wherein all webs are aligned with each other during a period when feeding friction is not being applied.

My invention has as its object the provision of devices having feeding peripheries, which may be extended or diminished at will, in combination with feed pin devices which will pick up the paper by engagement with aligned apertures therein, and feed it along for a short distance thereby aligning the various webs.

In connection with this adjustable feature, it is the object of my invention to provide a clamp for the paper which will engage and positively hold it during periods when the feeding mechanism is moving but not engaging the paper, since without some such device, the machine built according to my invention will not be entirely fool-proof.

As will be evident, to clamp the paper during the period when the feeding devices are not engaging the paper acts to prevent such slippage as will prevent the paper from shifting about before the pins come around to engage the holes therein, such slippage resulting from laying the hand on the paper, too much tension on the storage roll of paper, or like causes.

Furthermore the application of my invention in a clamping device has direct interest in any manifolding machine which feeds paper along by friction for a given space and then drops it, to be later picked up by an aperture engaging pin.

I accomplish the objects above set forth and other advantages to be noted by that certain construction and arrangement of parts to be hereinafter more specifically pointed out and claimed.

In the drawings, 55
Figure 1 is a side elevation showing the devices of my invention.

Figure 2 is a detail edgewise elevation of the adjustable device for operating the paper clamp, showing it also in side elevation 60 taken from the left of the main view.

Figure 3 is a detail of the upper roller.

Figure 4 is a plan and elevation of one of the roller disks.

Figure 5 is an edgewise view of one of 65 the adjustable paper feeding elements.

Figure 6 is a side elevation of the fixed member of the adjustable feed.

Figure 7 is a like view of the movable member of the said feed. 70

Figure 8 is a side elevation showing the end element of the adjustable clamp operating device.

Figure 9 is a side elevation of one of the intermediate elements of said clamp operating device. 75

Figure 10 is a side elevation diagrammatic of a simpler form offered.

It will be noted that I have shown my invention as applied in an autographic register, having a top 1, a writing table 2, and a suitable roller 3, not spring-pressed, which serves as the upper member of a rolling frictional feed for paper, said roll being provided with grooves 4 for the clearance of the feed pin or pins. 80 85

I have not shown the frame-work of the machine in detail as this forms no part of my invention, it being understood that there will be devices for storing paper and devices for leading it to the level of the writing table, whence it passes between the top and the table to the feeding devices, and from the feeding devices to a point where it may be torn off. 90 95

Machines of this character are often called upon to handle different lengths of slips, or in other words to issue at each feeding operation different length printed or unprinted sections of paper in a plurality of 100 copies.

The feed shaft 5 of the machine is to be rotated through ordinarily one complete revolution for each feeding operation although variants of this may be adopted 105 without departing from the spirit of my invention.

On this shaft are the desired number,

usually one or two, of feeding devices, depending whether built to be adjustable or not, which extend up through clearance slots 6 in the writing table, and engage the paper 5 between them and the upper roll.

These elements, be there one or more, are made up of segmental disks 7, having set screws 8 at their collar portions where they fit over the shaft 5, which will usually be 10 employed to lock them in a fixed position where they remain at all times, and of disks 9 of somewhat similar character, and having set screws 10 by means of which they are adjustably located radially of the shaft 5. 15 The disks 7 have reduced portions 11, which are terminated by a radially extending pin 12 for engaging apertures formed in the webs of paper. As shown in the drawings, the feed shaft handle 13 will preferably 20 be in locked position by the spring pin 14, when the feed pin has practically completed its operation and the main periphery of the disks or segment 7 has come into position to clamp the paper between it and the upper 25 roll.

The disks 9, are made up with their peripheries on the same arc as the main periphery of the disks 7, and they will thus form continuations of the feeding edges of 30 the disks 7 or overlap the said edges, dependent upon the adjustment of said disks 9 radially of the feed shaft.

It will be noted that the disks 9 carry pins 15 extending from their inner faces, and 35 that on the feed shaft there are circular disks 16 which maintain a constant contact with the upper roll, keep it away from resting against the writing table where it extends under it and give it a rolling motion.

40 Mounted on the under side of the writing table or on a stud, set at the desired position in the machine casing, is a lever 17 which is formed with a contact finger 18 at its extended end, said end being also 45 equipped with an anti-friction roller 19. The other end of the lever is provided with a stop block 20 and a post 21 on the lever carries a small spring 22, which acts against the writing table, to maintain the lever in a 50 position with its contact finger depressed.

The clearance slot in the writing table at the side where the clamp is located is wide enough for the finger to protrude through it and contact with the top or lid of the 55 machine without interfering with the feed pin movement. The normal depressed position will keep the clamping finger below the level of the writing table.

Mounted on the shaft 5 in a position to 60 contact with the anti-friction roller on the clamp lever, is a device preferably adjustable, that may be and is herewith shown as made up of a series of segmental plates arranged in a fan-wise relation.

65 The segment piece 23 has a collar portion

24, which is firmly set over the shaft 5 as by a set screw 25. The pieces 26 having like peripheries to the piece 23 are set loosely over the shaft and the end piece 27 is also loosely mounted on the shaft and kept in place by 70 means of a fixed collar 29.

All the segments except the piece 27 are equipped with pins 28, which engage in curved slots 30 formed in each piece, but the piece 23, so that as the piece 27 is pulled around, the segments will open fan-wise, the piece 23 forming one end of the fan, and the opening depending upon the extent to which the piece 27 is pulled. 75

On the piece 27 is a post 31, and on one 80 of the feed segments is the post 15 already mentioned. A link 32 held in place on each post by small thumb screws 33, and 34 respectively, links the two posts together, so that as the segment 9 is adjusted in its 85 position, the fan-like construction will be opened to correspond.

As will be noted, the parts are arranged 90 so that when the feeding periphery of the disk 9 terminates, the peripheries of the fan-like assembly will come into engagement with the anti-friction roller on the clamping device, so that the clamping finger will be forced up through the writing table slot 95 and hold the paper fast in its position at the end of the friction feed.

The piece 23 is arranged so that it will just be passing under the roller as the feed pin or pins come up ready for engagement with the alignment apertures in the paper being 100 fed.

It is not believed to be necessary to trace the sequence of operations, in order to note that the paper will be fed during each complete operation, through a distance corresponding to the extent of the segmental periphery, or the peripheries of the two or more segments, when used, minus the amount of overlap of the segment 9 and plus the distance through which the feed pin engages 105 and draws along the paper and that during the intermissions when no feeding is taking place, the paper will be clamped tightly against the lid of the machine. In the simpler form of Figure 10 where there is 110 but one segment as at 9^a, and no pin at all, the clamp will so regulate the feed in connection with the mutilated feeding periphery as to produce a good paper feed. 115

Also during the action of the feed pins 120 there is no friction against the paper, so that the webs may shift on themselves to come into alignment.

Having thus described my invention, what I claim as new and desire to secure 125 by Letters Patent, is:—

1. In a manifolding device, means having a limited contactual periphery and adapted to feed a plurality of webs of paper in conjunction with a co-operative roll, 130

- and a pin having supporting and moving means causing it to engage aligned apertures in the paper during a portion of the operation of said means when the periphery thereof is no longer contactual, and means automatically operated to hold the paper in a fixed position during the period of non-feeding by the pin or the said periphery.
2. In a manifolding device, a rotary member having a limited contactual periphery and adapted to co-operate with a roller for frictionally feeding a plurality of webs of paper, a movable pin having supporting and moving means causing it to engage aligned apertures in the paper, during a portion of the period of non-feeding by the said periphery, a clamping device, and means connected to and operating with the rotary member for moving said device into paper clamping position at periods of non-feeding by the pin or the said periphery.
3. In a manifolding device, a device adjustable for length of feeding engagement with paper webs, means for operating it to feed a plurality of webs of paper during a portion only of the movement of said device, said device moving through its complete cycle in one direction only, a clamping device for retaining the paper in a fixed position, and means for putting said clamping device into operation during non-feeding motion of the adjustable feeding device.
4. In a manifolding device, an adjustable device adapted to feed a plurality of webs of paper during a portion only of the movement of said device, a clamping device for retaining the paper in a fixed position, and means for putting said clamping device into operation during non-feeding motion of the adjustable feeding device, said adjustable feeding device having connection with the clamping device to automatically adjust it for duration of clamping action upon adjustment of the feeding device for duration of non-feeding movement.
5. In a manifolding device, the combination of a roll, a paper feeding device comprising a plurality of arc-shaped feeding peripheries adjustable to overlap and confine the feed to portions only of a complete circular movement of the device, a support for said device, said peripheries supported so as to contact with the roll and a clamping device, said device having means for throwing it automatically into action to hold the paper against movement during the period of inactivity due to the adjustment of the feeding peripheries.
6. A rotary feed element for machines of the character described, comprising a feed shaft, and a plurality of segment-shaped pieces having peripheries on the same arc, said pieces having means for mounting them on said shaft and means for retaining them in position of desired adjustment axially of said shaft, and means controlled from said shaft for holding the paper to be fed against movement while no peripheral portion is in feeding position.
7. In a paper feed for machines of the character described, the combination with an abutment roll, of a rotary element adapted to be revolved in contact with said abutment roll, said rotary element having means for adjusting the length of the contactual periphery thereof, a paper clamp, and means for operating it from the rotary element to clamp paper during the period of non-engagement of the rotary element during complete rotations thereof.
8. A feed element for machines of the character described, comprising a plurality of members mutually adjustable around a common axis, and having paper feeding means on their edges which lie in the same arc, and means for retaining said members in fixed, adjusted positions to form desired extensions of the same arc in different vertical planes, a paper clamp, and means for operating it automatically to clamp paper during portions of a complete arc not filled by said feeding edges.
9. In a manifolding register, a writing table, and a feeding means for feeding paper thereover in uniform lengths, said feeding means being adjustable to engage the paper for predetermined portion of each complete operation thereof, so as to feed different lengths of paper for single complete operations thereof, said device moving through its complete cycle in one direction only, and adjustable clamping means to hold paper against movement due to lapses in feeding resulting from adjustment of the feeding means.
10. In a manifolding machine, the combination of a shaft serving as a support, members arranged and adjustable about said shaft, and having segmental peripheries of the same arc, said members supported so as to contact with and feed webs of paper, said peripheries adapted upon adjustment to overlap, and form desired extensions of each other, a paper clamp and contact means connected to the shaft, and adapted to throw said clamp to clamping position, said contact means having an adjustable periphery.
11. In a manifolding machine, the combination of a shaft serving as a support, members arranged and adjustable about said shaft, and having segmental peripheries of the same arc, said members supported so as to contact with and feed webs of paper, said peripheries adapted upon adjustment to overlap and form desired extensions of each other, a paper clamp and contact means connected to the shaft, and adapted to throw said clamp to clamping position, said contact means having an adjustable periphery.

and means for adjusting said periphery controlled automatically by the adjustment of the first noted members about the said shaft.

12. In a manifolding register, the combination of a roller, a fan-like feeding device revolvably mounted, and adjustable about its axis to present desired feeding arcs against said roller, a paper clamp, and means to contact with and operate said clamp comprising a fan-like assembly of plates mutually adjustable about the same axis as the feeding device.

13. In a manifolding register, the combination of a roller, a fan-like feeding device revolvably mounted, and adjustable about its axis to present desired feeding arcs against said roller, a paper clamp, and means to contact with and operate said clamp comprising a fan-like assembly of plates mutually adjustable about the same axis as the feeding device, and connection between the two fan-like devices so that operation of the one to extend or diminish the fan spread will correspondingly extend or diminish the other.

14. In a manifolding device, the combination of a shaft serving as a support, a plurality of feeding segments of like periphery on the shaft, adjustable about the said shaft, a contact roll supported so as to cooperate with said segments to feed paper therebetween, a paper clamp and contact means for forcing said clamp to engaging position, comprising an extendable element connected to the shaft and connected to one

of the segments whereby the movement of the said segment extends or contracts the said extendable element.

15. In a manifolding machine, means having a limited contactual periphery and adapted to feed a plurality of webs of paper in conjunction with a co-operative roll and additional means automatically operated to hold the paper in fixed position during the period of non-feeding by the said periphery. 40 45

16. In a manifolding machine, a positively driven means, means contactual therewith and also movable for completing a grasp on the paper by the driven means, means for inhibiting the grasp between said driven and contactual means, and automatic means in addition to the above for engaging and holding the paper against movement during the period of inhibition. 50

17. In a manifolding machine, positively driven means, means contactual therewith and also movable for completing a grasp on the paper by the driven means, a movable pin having supporting and moving means causing it to engage aligned apertures in the paper, means for inhibiting the grasp of the driven and contactual means during the period of pin engagement and during an additional period when no grasp or pin engagement is present, and a device for engaging and holding the paper against movement during the period of non-grasp and non-pin engagement. 60 65

JOHN Q. SHERMAN.
